UNITED STATES PATENT OFFICE

161,758

LENS HOUSING FOR AUTOMOBILE LAMPS

Aloysius J. Kaminski, Detroit, Mich., assignor to
Chrysler Corporation, Highland Park, Mich., a
corporation of Delaware

Application May 20, 1950, Serial No. 10,069

Term of patent 7 years

(Cl. D48—32)

To all whom it may concern:

Be it known that I, Aloysius J. Kaminski, a citizen of the United States, residing in the city of Detroit, county of Wayne, and State of Michigan, have invented a new, original, and ornamental Design for a Lens Housing for Automobile Lamps, of which the following is a specification, reference being had to the accompanying drawing, forming part hereof, in which:

Fig. 1 is a front elevational view of a lens housing for automobile lamps, showing my new design;

Fig. 2 is a top plan view thereof;

Fig. 3 is a side elevational view;

Fig. 4 is a cross sectional view taken on the line 4—4 of Fig. 1; and

Fig. 5 is a perspective view of the lens housing for automobile lamps of my invention, the broken

line showing therein of a portion of the automobile being for illustrative purposes only.

I claim:

The ornamental design for a lens housing for automobile lamps, substantially as shown and described.

ALOYSIUS J. KAMINSKI.
